UNITED STATES PATENT OFFICE

JACOB MAZER, OF STONEHURST, UPPER DARBY TOWNSHIP, DELAWARE COUNTY, PENNSYLVANIA

SOUND ABSORBING UNIT AND METHOD OF MAKING SAME

Application filed October 25, 1930. Serial No. 481,152.

My invention relates to sound-absorbing units and a method of making the same, and more particularly to materials employed in the walls and ceilings of auditoriums, studios, etc., for absorbing sound and preventing reverberations thereof.

One object of my invention is to provide a unit that has great sound-absorbing capacity for a given area, and which may be readily constructed so that it will possess a desired predetermined sound-absorbing capacity.

Another object of my invention is to provide a sound-absorbing body whose surface may be conveniently given a decorative and pleasing appearance.

Still another object of my invention is to provide a sound-absorbing unit of generally improved characteristics.

One form which my invention may take is shown in the accompanying drawing wherein Figure 1 is a face view of a portion of a unit; Fig. 2 is an edge elevational view thereof; Fig. 3 is a plan view, on an enlarged scale, of one of the strips or ribbons entering into the structures of Figs. 1 and 2; Fig. 4 is a view similar to Fig. 3, but showing a ribbon of less width, and Fig. 5 is illustrative of the manner in which the ribbons of Figs. 3 and 4 may be creased or folded in incorporating them into a sound-absorbing unit.

The unit is composed of a number of strips or ribbons 6 that are creased and folded somewhat after the manner shown in Fig. 5, and a backing sheet or base 7.

The backing sheet 7 may be of any suitable material and is preferably flexible so that it may be bent to the contour of curved or angular wall surfaces to which the unit may be applied. The strips 6 may be of cloth, asbestos, very thin metal, or combinations of these materials, and may of course be of various thicknesses and widths.

Small quantities of adhesive material such as a suitable glue are applied at various points on the strip as indicated by the numeral 8, so that when the strip is folded as shown in Fig. 5, the strip will adhere to the backing sheet 7 and the folds thereof adhere to one

another, so that they will retain their folded positions as shown in Figs. 1 and 2.

In case a fire-proof unit is desired, the strips will be of non-combustible material such as thin metal or asbestos, and combinations of strips of metal, asbestos and cloth may be employed for the purpose of producing various decorative effects or for varying the sound-absorbing capacity of the unit. The thickness and width of the strips will also affect their sound-absorbing characteristics, not only because of differences in yieldability or flexibility of the strips, but by reason of the variation in the number and sizes of voids or recesses formed by the assembled strips. Furthermore, the strips while they may be of the same material, can be differently colored so as to produce certain ornamental appearances. Again, the completed unit may be painted so as to completely cover the exposed area thereof or to cover only the raised portions, leaving the depressions in the face of the unit uncolored.

By placing only small spots of adhesive on the strips they are, when folded, more yieldable than if they were completely covered with the adhesive, since each strip will have yieldability and sound-absorbing capacity throughout substantially its entire length notwithstanding the fact that it is more or less compactly folded.

To facilitate the folding of the strips and to at least partially predetermine the points at which the folds will occur when the strip is crushed endwise, I may provide slits or perforations in the same as indicated at 9 and 10 in Fig. 5. Obviously, there will be a tendency for the folds or creases to follow these weakened lines.

By the term "strips" which is employed in the specification and claims, I do not limit myself to ribbon-like material, but contemplate also, the use of large sheets of material which may be crushed or deformed in the manner of the strip of Fig. 5.

The unit of Fig. 1 may be given a smooth appearance by applying thereto a facing sheet of porous material such as perforated paper, loose mesh cloth, etc.

I claim as my invention:—

1. A sound-absorbing unit consisting of a plurality of strips crushed in a direction lengthwise thereof to form folds and held in assembled relation.
- 5 2. A sound-absorbing unit composed of strips disposed mainly flatwise in the plane of the unit each of which has transversely-extending folds, and means for holding the strips in assembled relation.
- 10 3. A sound-absorbing unit consisting of strips compressed endwise to form folds, and means for holding the said strips in their deformed positions.
- 15 4. A sound-absorbing unit consisting of strips compressed endwise to form folds and means for holding the said strips in their deformed positions, the said means comprising drops of adhesive placed at points spaced longitudinally of the strips.
- 20 5. A sound-absorbing unit composed of ribbon-like strips each having a plurality of folds along non-parallel lines extending in directions generally transversely of the strip.
- 25 6. The method of forming sound-absorbing units which comprises applying an adhesive to strips at points spaced longitudinally thereof and compressing the strips in a direction longitudinally thereof to cause the adhesive to retain the strips in depressed condition.
- 30 7. The method of making sound-absorbing units which comprises applying spots of adhesive to strips at points spaced longitudinally thereof, and compressing said strips in a direction longitudinally thereof against a backing sheet in order to deform the strips and to cause the adhesive to hold them against the backing sheet and to also hold them in depressed condition.
- 35 8. A sound-absorbing unit consisting of a sheet of material crushed in directions generally parallel to the plane thereof to form folds.
- 40 9. A sound-absorbing unit comprising a sheet of flexible material having folds or creases formed therein and lying approximately flatwise.
- 45 10. A sound-absorbing unit comprising a sheet of flexible material having folds or creases formed therein and lying approximately flatwise, the folds or creases extending in various directions relative to one another.
- 50 55 In testimony whereof I, the said JACOB MAZER have hereunto set my hand.
JACOB MAZER.
